UNITED STATES PATENT OFFICE.

JOHN W. NEUMANN, OF ST. LOUIS, MISSOURI, ASSIGNOR OF PART TO
CHARLES A. UNGER AND B. H. BENHOFF, OF ST. LOUIS, MISSOURI.

GAS-BURNER.

SPECIFICATION forming part of Letters Patent No. 782,202, dated February 7, 1905.

Application filed June 17, 1904. Serial No. 212,957.

To all whom it may concern:

Be it known that I, JOHN W. NEUMANN, a citizen of the United States, residing at St. Louis, State of Missouri, have invented certain new and useful Improvements in Gas-Burners, of which the following is a specification containing a full, clear, and exact description, reference being had to the accompanying drawings, forming a part hereof.

10 My invention relates to improvements in gas-burners; and it consists of the novel features herein shown, described, and claimed.

In the drawings, Figure 1 is a vertical central section on the line 1 1 of Fig. 2. Fig. 2 is a top plan view as seen looking in the direction indicated by the arrow 2 in Fig. 1. Fig. 3 is a top plan view, partly in section and parts being omitted. Fig. 4 is a bottom plan view of the burner-cap. Fig. 5 is a perspective of the burner-jets and nozzles. Fig. 6 is a view analogous to Fig. 1 and showing a modification. Fig. 7 is a bottom plan view of the burner shown in Fig. 6. Fig. 8 is a perspective of the nozzle shown in Figs. 6 and 7.

25 Referring to the drawings in detail, the supporting-frame comprises the annular wall 10, the supporting-feet 11, extending downwardly from the wall 10, the flange 12, extending horizontally inwardly from the upper edge of the wall 10, and the flange 13, extending upwardly from the wall 10 outside of the flange 12.

The mixing-chamber castings comprise a cylindrical body 14, resting upon the flange 12 within the flange 13 and secured in position by lag-screws 15, inserted upwardly through the flange 12, there being three inverted-funnel-shaped mixing-chambers 16 in said cylindrical body, and a flange 17, extending upwardly from said cylindrical body. In addition to the inverted-funnel-shaped portion 16 each mixing-chamber has the lower straight portion 16^a, extending downwardly, and the upper straight portion 16^b, extending upwardly. The upper face 14^a of the mixing-chamber casting is at right angles to the

straight portions 16^a and 16^b of the mixing-chamber.

The burner-cap comprises a central body 18, through which a lag-screw 19 is inserted 50 into the cylindrical body 14 to screw the cap in position, a plate 20, extending outwardly from the body 18, a perforated annular wall 21, extending downwardly from the outer edge of the plate 20, said wall having the gas- 55 perforations 22, and ribs 23, extending radially from the body 18 to the flange 21 to divide the space within the cap into three equal parts forming the distributing-chambers 24, said chambers registering with the three mix- 60 ing-chambers 16. Lugs 25 and 26 extend upwardly from the upper face of the cylindrical body 14, one upon each side of one of the ribs 23 to hold the cap in place with the distributing- 65 chambers 24 in registration with the mixing- chambers. The lower face 20^a of the plate 20 is parallel with the upper face 14^a of the mixing-chamber casting, and the gas-perfora- 70 tions 22 are close to said lower face 20^a.

The nozzles comprise the cap 27, bored out 70 and adapted to be attached to the supply-pipe 28 by a coupling 29, ears 30, extending radially from the cap 27 and secured to the bottom of the cylindrical body 14 by screws 31, and the jet-arms 32, extending radially from 75 the cap 27 and having jets 33 discharging upwardly into the funnel-shaped mixing-chambers 16. The jets 33 are connected to the bore in the cap 27. A valve 34 controls the supply of gas to the burner. The shutters 35 are 80 flat plates mounted between two screws 36 and adapted to slide on the lower face of the cylindrical body 14 in position to regulate the draft upwardly through the mixing-chambers. When the gas is turned on, it will pass through 85 the pipe 28 to the cap 27 and then to the jets 33. Then from the jets it will be discharged upwardly through the mixing-chambers. The force of these streams of gas will create a draft, drawing air upwardly past the shutters 90 35, and this air will be forced inwardly and compressed by the funnel shape of the mix-

ing-chambers, thereby causing a good mixture of the gas with the air. The discharge end of each jet 33 is above the lower end of the straight portion 16^a of the mixing-chamber 5 and below the lower end of the funnel-shaped portion 16. I have found by actual practice and years of experience that this peculiar shape and location of a jet and mixing-chamber, together with the peculiar shape 10 and relative location of the distributing-chamber 24 and the gas-perforations 22, produces a greatly-improved combustion over any of the ordinary forms of burners. The action of the gas passing from the jet 33 will start a draft of air the full size of the diameter of the straight portion 16^a of the mixing-chamber, and this volume of air passing upwardly into the funnel-shaped portion 16 is contracted and accelerated and forced into mixture with the 15 gas, and this mixture of air and gas passing through the reduced straight portion 16^b strikes directly against the lower face 20^a, rebounds and passes laterally over the upper face 14^a, strikes the annular wall 21, and then 20 passes through the perforations 22.

In the modification shown in Figs. 6, 7, and 8 I use a single mixing-chamber and a single jet-arm, but the same principles are maintained.

30 When the burner is in operation, the air immediately surrounding the mixing-chamber casting will be drawn upwardly by the flame, and the pressure of the cold air will force this upflowing air against the flame and concentrate the heat of the flame at a central point immediately above the center of the burner, and this concentrated heat striking the bottom of a vessel will be spread out all over the bottom and upwardly around the sides, there- 35 by forming a heat-jacket protecting the vessel from the cold air. The gas passing upwardly through the mixing-chambers will strike the center of the plate and be highly heated before passing through the openings 40 to the flame. This plate 20 is a heavy casting well adapted to hold and convey heat, and should not be confused with the ordinary thin pressed cap heretofore in use. These points 45 effect a great saving in the consumption of 50 gas and produce more perfect combustion.

I claim—

1. In a gas-burner, the mixing-chamber casting, comprising a cylindrical body, having an inverted-funnel-shaped mixing-chamber 55 16, and there being the straight portion 16^a extending downwardly from said funnel-shaped portion, and there being the straight portion 16^b, extending upwardly from the central portion; and the upper face 14^a of the 60 casting being at right angles to the discharge end of the mixing-chamber; a plate; the annular wall 21 extending downwardly from the plate, there being perforations 22 in said wall

close to the plate, the lower face 20^a of said plate being parallel with the upper face 14^a 65 of the mixing-chamber casting; and the nozzle 32, having the jet 33 discharging into the mixing-chamber, above the lower end of the straight portion 16^a.

2. In a gas-burner, the annular wall 10; the flange 12, extending inwardly from the upper edge of the wall; the mixing-chamber casting, resting upon the flange 12, said casting comprising the cylindrical body 14, having mixing-chambers, consisting of the inverted-funnel-shaped central portions 16, the lower straight portions 16^a and upper straight portions 16^b; the upper face 14^a of the casting being at right angles to the mixing-chamber; 70 the plate 20; the annular wall 21, extending downwardly from the plate and resting upon the mixing-chamber casting and having gas-perforations 22 immediately below the plate, and the lower face 20^a of the plate 20 being parallel with the upper face 14^a of the mixing-chamber casting; the cap 27; ears 30, extending radially from the cap and secured to the mixing-chamber casting; and the jet-arms 32 extending radially from the cap and having jets 33 discharging into the mixing-chambers 75 above the lower ends of the straight portions 16^a.

3. In a gas-burner: the mixing-chamber casting comprising, a cylindrical body having a plurality of inverted-funnel-shaped mixing-chambers 16; there being the straight portions 16^a extending downwardly from said funnel-shaped portions; and there being the straight portions 16^b extending upwardly from the central portions; and the upper faces 14^a 90 of the casting being at right angles to the discharge ends of the mixing-chambers; a plate; an annular wall extending downwardly from the plate; there being perforations in said wall close to the plate; the lower face 20^a of said plate being parallel with the upper faces 14^a of the mixing-chamber casting; radial ribs 95 extending downwardly from the plate inside of the flange to divide the space within the flange into as many parts as there are mixing-chambers; and nozzles having jets discharging 100 into the mixing-chambers; substantially as specified.

4. In a gas-burner: the mixing-chamber casting comprising, a cylindrical body having 115 a plurality of inverted-funnel-shaped mixing-chambers; there being straight portions 16^a extending downwardly from said funnel-shaped portions; and there being straight portions 16^b extending upwardly from the central portion; and the upper faces 14^a of the casting being at right angles to the discharge 120 ends of the mixing-chambers; a plate; a central body extending downwardly from the plate; a perforated annular wall extending 125 downwardly from the plate; ribs extending

radially from the annular wall and downwardly from the plate to divide the space into distributing-chambers communicating with the mixing-chambers; means of holding the 5 distributing-chambers in registration with the mixing-chambers; and nozzles discharging into the mixing-chambers; substantially as specified.

In testimony whereof I have signed my name to this specification in presence of two sub- 10 scribing witnesses.

JOHN W. NEUMANN.
